US00D980226S

(12) **United States Design Patent** (10) Patent No.: **US D980,226 S**
(45) Date of Patent: ** Mar. 7, 2023

(54) **KEYBOARD WITH A TABLET PROTECTIVE CASE**

(71) Applicant: **Zhijun Hu**, Shenzhen (CN)

(72) Inventor: **Zhijun Hu**, Shenzhen (CN)

(**) Term: **15 Years**

(21) Appl. No.: **29/823,948**

(22) Filed: **Jan. 20, 2022**

(51) LOC (14) Cl. **14-02**

(52) U.S. Cl.

USPC **D14/440**

(58) **Field of Classification Search**

USPC D14/250, 440, 432, 447

CPC ... H04B 1/3888; B32B 38/1841; B32B 37/26;

G06F 1/166; G06F 1/1667

(57) **CLAIM**

The ornamental design for a keyboard with a tablet protective case, as shown and described.

DESCRIPTION

FIG. 1 is a perspective view of a keyboard with a tablet protective case, showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;

FIG. 9 is another perspective view showing the design in a partially opened configuration;

FIG. 10 is another perspective view showing the design in a partially opened and detached configuration;

FIG. 11 is another perspective view showing the design in a partially opened and twenty five degree swiveled position;
FIG. 12 is another perspective view showing the design in a partially opened and ninety degree swiveled position;

FIG. 13 is another perspective view showing the design in a partially opened and one hundred and eighty degree swiveled position;

FIG. 14 is another perspective view showing the design from FIG. 9 in a fully opened configuration; and,

FIG. 15 is another perspective view showing the design from FIG. 14 in a closed and one hundred and eighty degree swiveled position.

The broken lines depict features of the keyboard with a tablet protective case that form no part of the claimed design.

1 Claim, 15 Drawing Sheets
